UNITED STATES PATENT OFFICE.

ALBIN PETERSON, OF PESHTIGO, WISCONSIN.

STAMP-MOISTENER.

1,276,408.

Specification of Letters Patent. Patented Aug. 20, 1918.

Application filed August 2, 1917. Serial No. 184,106.

To all whom it may concern:

Be it known that I, ALBIN PETERSON, a citizen of the United States of America, residing at Peshtigo, in the county of Marinette and State of Wisconsin, have invented new and useful Improvements in Stamp-Moisteners, of which the following is a specification.

This invention comprehends generally 10 improvements in stationery and more particularly has reference to a stamp-moistener.

As the primary aim and object the present invention contemplates the provision of a device of the above character designed to be 15 operated when a stamp is pressed thereagainst for assuring of the proper moistening of the stamp preparatory to applying the same.

More particularly this invention embraces 20 the provision of a device of the above mentioned character wherein improved coöperative moistening members are employed one of which is designed to be moved downwardly when a stamp is pressed thereagainst 25 while the other is adapted to be moved upwardly and contact with the first member to assure of an effective moistening of the stamp.

It is a more specific object of this invention 30 to provide a device of the above character wherein improved resilient means are provided for normally holding the dampening or moistening pad within the water chamber and is capable of being compressed 35 when the stamp is placed against the upper member to permit downward movement of the latter and the consequent moistening of the stamp.

Among the other aims and objects of this 40 invention may be recited the provision of a device of the character described with a view to compactness, and in which the number of parts are few, the construction simple, the cost of production low and the efficiency 45 high.

Other improvements and novel details in 50 the construction and arrangement of the various parts of the apparatus will be brought out more in detail in the description to follow, which for a clear understanding 55 of the present invention should be considered in connection with the accompanying drawings forming a part hereof, and wherein is disclosed for the purpose of illustration a convenient and satisfactory embodiment of the invention. It is to be noted

in this connection that minor changes in the construction and arrangement of parts may be made without departing from the principle of operation of the various parts. 60

The invention is clearly illustrated in the accompanying drawings, in which:—

Figure 1 is a longitudinal section taken through the invention showing the stamp moistening means in an inactive position; 65

Fig. 2 is a fragmentary longitudinal section showing the moistening means arranged in an operative position;

Fig. 3 is a transverse section taken on line 3—3, Fig. 1, in the direction in which 70 the arrows point;

Fig. 4 is a top plan view of the invention; 75 Similar characters of reference are employed in all the above described views, to indicate corresponding parts.

Referring now, more particularly to the accompanying drawings, there is provided a main casing 1 of a rectangular configuration the side walls of which are reduced as at 2, adjacent the front end 3 while midway 80 the front end 3 and the rear end 4 a transverse partition 5 is mounted, being preferably integral with the inner surfaces of the side walls and the bottom of the casing forming compartments 6 and 7 the former 85 of which constitutes a water chamber.

With a view toward providing improved stamp moistening means a support, indicated in its entirety by the numeral 8 is mounted within the water chamber 6 and comprises 90 opposed front standards 9, opposed intermediate standards 10 and oppose rear standards 11 suitably connected to each other by cross bars 12 and 13. The standards 10 terminate about midway the height of the 95 casing 1 in bearings 14 in which are journaled the respective ends of a shaft 15. A drum 16 is carried by the shaft while carried tangentially of the periphery thereof is a transversely arranged pad 17 for a purpose 100 that will presently appear. Cog wheels 18 are carried by the shaft adjacent the respective ends thereof. Arms 19 are now pivotally mounted through the instrumentality of pintles 20 to the upper ends of the rear 105 standards 11 of the support 8 and are normally arranged substantially in close relation with the upper edge of the casing 1 being formed on their lower edges with toothed segments 21 the teeth of which are arranged 110 in engagement with the teeth of the cog wheels 18. Suitable resilient means such as

coil springs 22 are now employed and have their upper and lower ends respectively connected to the lower cross bars 12 of the support 8 and to the under surfaces of the arms 5 19 adjacent the outer ends thereof being arranged about rods 23 which terminate approximately midway the height of the rear portion of the casing serving merely to guide and properly position the spring; the latter 10 being of course designed to normally hold the arms above the upper edge of the casing, as indicated in Fig. 1, so as to consequently maintain the pad 17 within the water chamber 6. In this connection it is to be noted 15 that a weight 24 formed on the drum serves to counter-balance the action of the pad and assure of the easy partial rotary movement of the drum when the arms are pressed downwardly which action, owing to the arrangement 20 of the toothed segments 21, causes the pad to be positioned adjacent the upper edges of the casing. Coöperating with the pad is the other improved moistening member against which a stamp is adapted to be 25 pressed. This member consists of a rectangular frame, indicated in its entirety by the numeral 25 the front and rear portions being formed from angle irons as at 26 while the side portions are arranged in an inverted 30 channel formation as at 27 and designed to straddle the arms adjacent the outer ends thereof, as indicated. A piece of reticulated material such as a perforated sheet 28 is carried by the frame and is covered with a piece 35 of cloth 29 arranged on the outer surface thereof. By this arrangement it is to be appreciated that the frame carrying the perforated sheet although carried with the arms may be removed therefrom at times when 40 it is desired to pour water into the casing and by reason of the particular construction when the gummed surface of a stamp, not shown, is held against the piece of cloth and a downward movement imparted to the 45 frame the arms will swing about their pivots and as soon as the toothed segments 21 engage the cog wheels 18 the drum will be partially rotated so as to move the pad 17 upwardly until the perforated sheet 28 contacts with the upper surfaces of the pad 50 which being formed preferably of felt causes the water to pass through the perforations while the cloth assures an equal distribution of the water and consequently the easy and 55 quick dampening and moistening of the stamp, not shown. Of course, as soon as the parts are released they will be automatically returned to the former position owing to the tension of the coil springs 22.

60 In view of the foregoing description it is believed that a further detailed description of the operation of the invention is entirely unnecessary. Likewise it is believed that the advantages of the invention will be 65 readily apparent.

As many changes could be made in the above construction and many apparently widely different embodiments of this invention could be made without departing from the scope thereof and it is intended 70 that all matter contained in the above description or shown in the accompanying drawings shall be interpreted as illustrative and not in a limited sense. It is also to be understood that the language used in 75 the following claims is intended to cover all the generic and specific features of the invention herein described and all statements of the scope of the invention which as a matter of language might be 80 said to fall therebetween.

Having thus fully described the invention, what is claimed as new and desired to be secured by Letters Patent is:—

1. A device of the character described, including a casing formed with a water chamber, a drum journaled in the sides of the casing above the water chamber, a pad carried by the outer periphery of the drum, pivotally mounted arms in the casing and 85 operably connected to the drum so that upon downward movement of the arm the drum will be partially rotated so as to position the pad adjacent the upper edge of the casing, a frame carried removably on the arms, a perforated sheet carried by the frame and against which a stamp is to be arranged so that upon downward movement of the arms the pad will consequently press against the perforated sheet so as to moisten the stamp, 90 and resilient means for normally holding the arms and the frame in a raised or inactive position.

2. A device of the character described including a casing provided with a water 105 chamber, a shaft journaled through the casing above the chamber, a drum carried by the shaft, a pad carried by the periphery of the drum and normally positioned within the water chamber, cog wheels carried by 110 the shaft adjacent the respective ends thereof, a pair of arms pivotally mounted in the casing adjacent the upper edge thereof, a frame mounted on the arms and movable with the arms, a perforated sheet carried by 115 the frame, a cloth covering for the perforated sheet, toothed segments depending from the arms and engageable with the teeth of the cog wheels so that upon downward movement of the frame the drum will 120 be partially rotated so as to position the pad beneath the plate, and resilient means for normally maintaining the arms in a raised or inactive position.

3. A device of the character described including a casing having a water chamber formed therein, a drum journaled in the casing above the chamber, a pad carried by the periphery of the drum, a movably mounted perforated sheet in the casing 125 130

above the drum and operably connected to the drum so that upon downward movement of the plate the drum will be partially rotated so as to position the pad beneath the 5 plate, and resilient means for automatically returning the plate to a raised or inactive position.

4. A device of the character described including a casing having a water chamber 10 therein, a support mounted in the water chamber, a shaft journaled in the support, a drum carried by the shaft, a pad carried with the outer periphery of the drum and tangentially thereof, cog wheels carried by the shaft adjacent the respective ends thereof, a pair of arms pivotally mounted on the upper end of the support adjacent the upper edge of the casing and the opposite sides thereof, toothed segments

depending from the under edges of the arms 20 and meshing with the teeth of the cog wheels, a rectangular frame removably mounted on the upper edges of the arms, a perforated sheet carried by the frame, a cloth covering the perforated sheet, guide 25 rods carried by the support, and coil springs disposed about the guide rods and having their respective ends bearing against the lower portion of the support and the under surfaces of the arms for normally holding 30 the arms in a raised position and the pad within the chamber and adapted to be compressed upon downward movement to partially rotate the drum and arrange the pad beneath the perforated sheet. 35

In testimony whereof I affix my signature.

ALBIN PETERSON.
